[57] CLAIM

The ornamental design for a binder, shown and described.

DESCRIPTION

FIG. 1 is a top perspective view of a binder showing our new design in a fully opened position;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof; FIG. 7 is a left side elevational view thereof; FIG. 8 is a top plan view thereof in a fully closed position;

FIG. 9 is a front elevational view thereof, the undisclosed rear being flat and plain; and

FIG. 10 is a right side elevational view thereof, the undisclosed left side being substantially the same.
